UNITED STATES PATENT OFFICE.

LAURITS MILLER, OF MONTREAL, QUEBEC, CANADA.

FURNACE.

Application filed October 6, 1924. Serial No. 741,925.

The invention relates to a furnace as described in the present specification and illustrated in the accompanying drawings that form part of the same.

5 The invention consists essentially of the novel features of construction pointed out in the claim for novelty following a description containing an explanation in detail of an acceptable form of the invention.

10 The objects of the invention are to increase the heating surfaces and thereby economize in the consumption of fuel; to facilitate the distribution of heat in radiating hot water heating systems; to construct a furnace applicable to the use of various known kinds of fuel; to insure the utilization to the fullest extent possible of the heating gases and obtain the maximum efficiency from a given quantity of fuel; and generally to provide a durable and serviceable furnace at a low cost in respect to production and which is economical in operation for the householder and other users.

25 In the drawings, Figure 1 is an elevational view of the furnace having the front broken to disclose the fire tubes.

Figure 2 is a cross sectional view on the line 2—2 in Figure 1.

30 Figure 3 is a vertical sectional view on the line 3—3 in Figure 2.

Figure 4 is a vertical sectional view on the line 4—4 in Figure 2 showing a coal fire grate and box.

35 Figure 5 is an enlarged perspective detail of a draught plate.

Figure 6 is a plan view of the gas burner arrangement in a gas furnace.

Figure 7 is a plan view of the furnace with the top cover removed.

40 Figure 8 is an enlarged sectional detail of the intercommunicating passage and valve.

Like numerals of reference indicate corresponding parts in the various figures.

45 Referring to the drawings, the casing of the furnace is in sections 10, 11 and 12 or as many more as desired each section being a distinct part of a water jacket and indicated by the numerals 13, 14 and 15. The sections are joined at the lower ends by the tubular passages 16, 17 and 18, so that the return pipes 20, 21 and 22 into the lower ends of the jackets 13, 14 and 15 will deliver water for a common level in the three furnace sections. At the upper ends the jacket sections are connected by the passages 23, 24

and 25 each passage having a central swing gate 19, which opens only at the increase of pressure in one compartment as compared with the pressure in the adjoining compartment.

50 Each section is formed with a hot water chamber denoted by the numerals 26, 27 and 28 having the fire tubes 29, 30 and 31 respectively extending from the heads 32, 33 and 34 and 35, 36 and 37. The chambers 26, 27 and 28 extend from the upper end of the casing downwardly and terminate towards the lower end leaving sufficient room for the firebox, gas or oil burners or other fuel installation. The said chambers communicate with the jackets 13, 14 and 15 so that with the numerous fire tubes there is a great heating surface, besides as the chambers are elliptical in cross section the inner walls 38, 39 and 40 present wide arc-shaped surfaces for the complete height of the chambers.

55 The outlet pipes 41, 42 and 43 lead from the upper ends of the chambers 26, 27 and 28 and are distributed as desired to the radiating system, each outlet pipe having its own return pipe, thereby providing a means whereby the circuits can be distinct if desired and directed to particular parts of a house or building making it possible to increase the heat in one part and reduce in another part or, if required, shut it off entirely in the one part and maintain it in the others.

60 The gas burners 44 and 45, 46 and 47 and 48 and 49 are shown as the preferable heating means employed, each set being apportioned to a hot water chamber. All the gas burners are connected to a main gas feed pipe and in the leads from the latter gas cocks are shown for cutting off the feed, the gas cocks for the burners 45, 47 and 48 being preferably operated from a thermostat 50. This thermostat regulation is not shown in detail as it is altogether another art, but the thermostats 50 are shown as governed by the heat of the return water, which is perhaps a safer way to regulate the furnace.

65 The plate dampers 51, 52 and 53 form covers for the upper ends of the hot water chambers 26, 27 and 28 and have guide rods 54 and 55 fitting into a fire tube hole at each end of the nests of tubes and these rods direct the plates over the heads 32, 33 and 34 to cover in the fire tubes 29, 30 and 31 and thereby effectually shut off draught. These

damper plates 51, 52 and 53 are operated from the central stems 56 by the rocker arms 57 connected by the links 58 to the stems 56.

The other ends of the rocker arms 57 are shown with the ratchet bar 59 engaged by the pawl 60 spring-held thereto. Many other ways of lifting these plates could be shown but for the present the above will be sufficient, as most likely they will be connected up to a thermostat operating mechanism.

The baffle plate 63 closes in the space between the walls 38, 39 and 40 at the upper end, and the furnace top 61 fits over the upper end of the casing and has a flue pipe from the centre thereof, this top leaving sufficient room for the opening and closing of the plate dampers aforesaid.

The gas burners are also elliptical in shape 20 and the middle ones 44, 46 and 48 are supposed to be connected all the time, while the furnace is in use and burn continuously through suitable spreading jet holes. The burners 45, 47 and 49 are operated when 25 wanted and are preferably controlled by a thermostat and have jets pointing upwardly and to the jacket walls.

Another figure shows a coal grate and coal fuel but gas and oil are likely to be 30 used more particularly in cities where they have a plentiful supply of gas.

In the operation of this furnace the central gas burners are lighted from a pilot light 62, which is kept going continuously. 35 So soon as additional heat is required the outer burner will then come into more general use.

The heat is regulated by the gas consumed and also by the circulation of air constituting hot gases through the fire tubes, and this 40 is facilitated by raising the plate dampers,

of course with a coal fire the tubes are all important for draft and the heating gases are used to their fullest extent in the multiplicity of tubes in the three hot water chambers. 45

It will readily be seen how the gases can be directed to one or more of the hot water chambers through the operation of the damper plates, therefore a selection can always be made or the three can be run to their limit. 50

The economy in the consumption of fuel can readily be seen in the simple means employed for shutting off a section of the furnace and the value of this device as a gas furnace must be emphasized as it is very easy to heat the water for the heating surface throughout is very great, thus dividing the water into comparatively thin streams 55 which quickly absorb the heat and pass upwardly to the radiating system. 60

What I claim is:—

A furnace comprising a plurality of duplicate individual vertical fire tube boilers having curved walls and mating longitudinally extending joint-forming edges, said boilers being so dimensioned as to provide when in assembled relation a circular casing and a central vertical flue, the outer walls of said 70 boilers being downwardly extended to provide a fire box beneath the fire tubes and said main central flue, draft regulators covering the upper ends of the fire tubes of said 75 boilers and adjustable thereon, and a hood forming the top of the furnace and enclosing the upper ends of said boilers and said main central flue and having a suitable chimney therefrom.

Signed at Montreal, Canada this 12th day 80 of September 1924.

LAURITS MILLER.
